[57] CLAIM

The ornamental design for a fountain brush, as shown.

DESCRIPTION

FIG. 1 is a side elevational view of a fountain brush showing our new design, the opposite side being a mirror image;

FIG. 2 is a top plan view thereof;

FIG. 3 is a bottom plan view thereof;

FIG. 4 is a front end elevational view thereof, the top portion of the handle being shown on an enlarged scale; and

FIG. 5 is a rear end elevational view thereof.
